UNITED STATES PATENT OFFICE.

LEWIS M. LAWRENCE, OF BIRMINGHAM, ALABAMA.

BUMPING-POST.

1,091,150.

Specification of Letters Patent. Patented Mar. 24, 1914.

Application filed July 5, 1911. Serial No. 637,040.

To all whom it may concern:

Be it known that I, LEWIS M. LAWRENCE, a citizen of the United States, residing at Birmingham, in the county of Jefferson, 5 State of Alabama, have invented a new and useful Improvement in Bumping-Posts, of which the following is a specification.

My invention is a buffer or bumping post arranged at the end of railway spur tracks 10 to arrest a train or cars running thereon, the principal feature of which is cross anchor beams, and two pair of longitudinal beams inclined downward from the rear to the front, and top cross beams, and uprights set 15 deep in the earth for additional anchorage. The upright in the center is the bumper proper.

In the accompanying drawing Figure 1 is a perspective view of the structure with 20 the front to the left. Fig. 2 is a sectional view looking from the middle to the left side. Fig. 3 is the center one of the uprights which comprise the bumper proper.

The numerals refer to the various parts 25 in the different views.

The rail road rails 1—1. 1 designates the railroad rails, 2 the common crossties; and 3, 4 and 5 the cross under the rails and spiked to them in the ordinary way.

30 Two pair of longitudinal beams 6—6 and 7—7 rest on the ends of the anchor beams. Beams 6 lap over beams 7 in part. A shoulder is cut in the under edge of the front end of beam 7 and the top edge is beveled. This 35 shoulder rests on and abuts anchor beam 4 which gives beams 6 and 7 an incline from the rear to the front.

Two top cross beams 8 and 9 placed some 40 seven inches to the rear of anchor beam 4 and blocks 10—10 between the two beams. Anchor beam 4 and the rear top cross beam 9 are encircled by metal links 11—11 best seen in Fig. 2. All the joints are tied by metal links 12—12 and 13—13 and 14—14.

45 In this seven inch space I set uprights 15—15 digging deep in the earth for additional anchorage. The uprights rest against the rear of anchor 4 and the front of the top cross beam 8. The upright in the

center serves the double purpose of bumper 50 16 proper and additional anchorage. It is molded with a hole in the upper end of it, see Fig. 3. This hole is larger at the front than at the rear and is to be fitted with a block of wood grainwise for the draw head 55 of the car to play on.

From the foregoing it is seen that here is a tie or lock or anchor on the earth, the structure of which will admit of any conceivable strength, can be built to any wants, 60 stand if you want it to stand or give yet not break, plows the earth much as a snow plow plows a bank of snow.

What I claim is—

1. In a bumping post the combination 65 with a pair of longitudinal side frames, inclined from the rear to the front, of transverse members mounted thereon and spaced apart by blocks, and vertical posts having their upper ends supported by said transverse members, a transverse member 4 mounted beneath the said longitudinal members and lying against the front of the vertical posts, and means to tie the transverse members together and to tie all said elements to the side frames as described.

2. In a bumping post the combination with side frames mounted on transverse anchor beams and secured thereto, of a plurality of transverse timbers mounted upon 80 the side frames, and a vertically disposed post extending above and below the plane of said side frames the lower end of said post being adapted to secure said bumping post against displacement substantially as described.

3. In a bumping post the combination of vertical members extending below and above the plane of side members and supported at the top and rear by top cross members, and 90 below the side members and at the front by a cross anchor member and with the means of tying all of the elements together as described.

LEWIS M. LAWRENCE.
